Harry C. Crozier Inventor

By *Charles L. Morris*,
Attorney

UNITED STATES PATENT OFFICE.

HARRY C. CROZIER, OF PHOENIX, ARIZONA.

LOOSE-LEAF BINDER.

Application filed August 4, 1922. Serial No. 579,745.

To all whom it may concern:

Be it known that I, HARRY C. CROZIER, a citizen of the United States, residing at Phoenix, in the county of Maricopa and State of Arizona, have invented new and useful Improvements in Loose-Leaf Binders, of which the following is a specification.

This invention relates to loose-leaf binders and proposes the construction of a device of the class designated in which the leaves are detachably secured in place by leaf-holding posts cooperating with a longitudinally slideable latching bar carried by the cover of the binder.

One of the objects of the invention is the provision of leaf-holding posts of uniform diameter and devoid of lateral undercut portions which would tear the edges of the apertures in the leaves when the latter are being removed from or replaced within the binder.

Another object of the invention is the construction of a loose-leaf binder including a cover and a plurality of leaf-holding posts each provided with a transverse bore adjacent an end thereof and a slot of less width than the diameter of said bore, formed in the end of said post and joining said bore, there being a longitudinal latching rod carried by the cover and extending through the transverse bores in the posts, having portions of larger diameter fitting said bores and adjacent portions of smaller diameter fitting said slots, said rod being selectively reciprocable to bring either of said adjacent portions into registry with said bores and slots.

Still another object of the invention is the provision of the leaf-holding posts with latching rod receiving slots in an end thereof and rod-engaging bores communicating with said slots, and a latching rod carried by the cover of said binder having adjacent portions of two diameters, one fitting the bores and the other the slots, said rod being brought into latching relation with the posts by movement of the cover, aligning said rod with said slots and causing those portions of the rod of smaller diameter to enter the same, and then pushing said rod longitudinally to cause the portions of larger diameter to enter the bores of said posts.

A further object of the invention is to make the posts alike at both ends and therefore reversible and interchangeable.

A still further object of the invention is

the provision of a latching rod which is not subjected to twisting strains in the normal operation of the device and which if forcibly twisted will not be rendered inoperative. 60

With the above and other objects in view, my invention consists in the improved loose-leaf binder illustrated in the accompanying drawings, described in the following specification, and particularly claimed, and in 65 such variations and modifications thereof as will be obvious to those skilled in the art to which my invention relates.

In the drawings accompanying and forming a part of this specification, and wherein 70 the preferred embodiment of my invention is illustrated:—

Figure 1 is a perspective view of my improved loose-leaf binder in unlatched position with the leaves removed. 75

Figure 2 is a view in elevation showing the latching rod in unlatched position.

Figure 3 is a similar view showing the latching rod in latching position.

Figure 4 is a view in perspective showing 80 one of the leaf-holding posts.

Referring now in detail to the several figures, the numeral 1 represents the cover of a loose-leaf binder having the back portion 2 and the flexible foldable hinge portion 3. 85 A metal hinge-strip 4 is secured longitudinally along the foldable hinge portion 3 on each side of the back portion 2 and consists of a sheet metal blank bent upon itself to form a longitudinally extending bore 5 and 90 cut away at intervals as at 6 after the manner of a piano hinge. The strips 4 are rigidly secured to both sides of the cover 1. A latching rod 7 is slidably mounted within the bore 5 and extends the full length of the 95 binder, being limited in its reciprocatory movement by a slightly upset portion 8 of said rod which has a range of movement between the front and back walls 9 and 10 of a recess cut out from the strip 4 near one end thereof. The latching rod is of two diameters, alternating throughout the length of said rod, the parts 11 of larger diameter fitting the bore 5 and being projected into the cutaway portions as shown in Figure 3 when 105 the latching rod occupies an inward position. When the latching rod is pulled out as shown in Figure 2, the parts 12 of small diameter project into said cutaway portions. There are two latching rods 7, engageable within 110 the opposite ends of the leaf-holding posts 13.

The latter are cooperably arranged with

respect to the latching rods, each of said posts comprising an arcuate bar having its ends tapered as shown at 14 in Figure 4 and being provided adjacent its ends with transverse bores 15 of such diameter as to afford a close sliding fit for the parts of the rods 7 of larger diameter. The ends of the posts 13 are provided also with slots 16 which open through the ends of said posts and 10 communicate with the bores 15. The slots are of such width as to admit the entrance therethrough of the parts 12 of the latching rods of smaller diameter but to prevent the escape therefrom of the parts 11 of larger 15 diameter.

The posts 13 are assembled into position as shown in Figure 1 by withdrawing the lower rod 7 to the position shown in Figure 2 and then placing the slotted ends of the 20 posts over the parts 12 of smaller diameter.

The rod 7 is then shoved inwardly so that the parts 11 of larger diameter come into the bore 5. Since said parts of larger diameter cannot escape through the slots 16 it is impossible for the posts to become detached unless 25 the lower rod be subsequently withdrawn.

A suitable number of perforated leaves are arranged upon the posts 13, and are secured from removal by swinging the free 30 side of the cover upwardly and aligning the several parts of smaller diameter of the upper rod 7 with the slots in the tops of the posts and then causing said parts of smaller diameter to enter the bores 15 by slightly 35 depressing the free side of the cover. The upper latching rod is then pushed inwardly so that its parts of larger diameter enter the bores in the upper ends of the posts 13 securely latching them to the binder cover and 40 preventing the loss or withdrawal of the leaves until the upper latching rod is released.

By making the slots 16 in the ends of the posts 13, the cylindrical surfaces of said 45 posts are rendered free from undercut recesses or other irregularities which would tend to catch or tear the leaves as they are withdrawn from and replaced upon the posts. Moreover, the endwise location of 50 said slots makes them visible to the user of the binder while placing the upper rod 7 in engagement with the posts thus facilitating the alignment of said rod with the slots.

It has previously been attempted to devise 55 a latching rod having flat portions in a single plane adapted to enter slots in a plurality of leaf-holding posts, and then latched by turning said rod so as to present the broad side of said flattened portions to the 60 slots. It sometimes happens, however, in a construction embodying this feature that the parts bind to such an extent that there is a twisting of the rod in the attempt to turn it to latching or unlatching position so that 65 the flattened portions no longer lie in the

same plane and are therefore unable simultaneously to enter the slots, thus rendering the device inoperative. The present invention is an improvement upon this construction since the latching rod is operated reciprocally and without subjecting it to a twisting strain. And were it possible through misuse to twist the latching rod the operation of the binder would not be affected since the parts of said rod are cylindrical.

It will be understood that various changes may be made in the form and relation of parts to suit different requirements of use, and that the invention, therefore, is not limited to the precise details of construction and arrangement shown.

Having described my invention what I claim as new and desire to secure by Letters Patent, is:—

1. A loose-leaf binder including in combination, a cover, a leaf-holding post carried by said cover, said post having a transverse bore therethrough adjacent one end and a slot of smaller width than the diameter of the bore opening from the end face of said post into said bore, a reciprocable latching rod secured to said cover and alignable with the bore in said post, said rod having adjacent parts of two diameters, 95 one fitting said slot and the other said bore, said rod being selectively longitudinally shiftable to bring the part of smaller diameter into alignment with said slot to enter therein and to telescope the part of larger 100 diameter within said bore.

2. In a loose-leaf binder, including in combination, a cover, a plurality of leaf-holding posts carried by said cover, said posts having transverse bores therethrough adjacent the ends and slots of smaller width than the diameters of the bores opening from the end faces of said posts into said bores, a pair of reciprocable latching rods secured to said cover and alignable with the bores in said posts, said rods having adjacent parts of two diameters cooperable with said posts, the parts of smaller diameter fitting said slots and the parts of larger diameter fitting said bores, each of said rods being selectively longitudinally shiftable to bring the parts of smaller diameter into alignment with said slots to enter thereinto or escape therefrom, and to bring the parts of larger diameter within 110 said bores.

3. A loose-leaf binder including in combination, a cover, leaf-holding posts carried by said cover, said posts having transverse bores therethrough adjacent one end, and slots of smaller width than the diameter of the bores opening from the end faces of said posts into said bore, a hinge strip secured to said cover forming a bore, having cutaway portions vertically alignable with 125

- said posts, a latching rod reciprocably slideable within the bore of said hinge plate and having parts of two diameters selectively presentable within said cutaway portions
- 8 upon reciprocation of said latching rod, the parts of smaller diameter being adapted to enter within the slots in said posts and the parts of larger diameter telescoping within the bores of said posts.
- 10 4. In a loose-leaf binder, a reversible leaf-holding post having transverse bores there-
- through at its opposite ends and slots of less width than the diameter of said bores opening through the opposite end faces of said post into said bores.
- 15
- In testimony whereof I have hereunto set my hand in presence of two subscribing witnesses.

HARRY C. CROZIER.
